REGISTER FOR HEATING PLANTS

Filed July 17, 1930

UNITED STATES PATENT OFFICE

JOHN J. BURGESS, OF ROCK ISLAND, ILLINOIS, ASSIGNOR TO ROCK ISLAND REGISTER COMPANY, OF ROCK ISLAND, ILLINOIS, A CORPORATION OF ILLINOIS

REGISTER FOR HEATING PLANTS

Application filed July 17, 1930. Serial No. 468,670.

This invention relates to registers for hot air heating plants and ventilation and more particularly to the construction and means for operating the louvres of a register.

5 An object of the invention is to provide improved means for causing the louvres to open and close with ease and smoothness and without noise and to provide means for retaining them in the open or closed position.

10 Another object is to provide a construction by which the assembled register box containing the louvres has smaller thickness, requiring less space for storage on warehouse shelves.

15 In the drawing:

Figure 1 is an end view of the assembled register box, with the end rail nearest the observer removed.

Figure 2 is a bottom view of the assembled 20 registered box.

Figure 3 is a section of end rail 5, seen in Figures 1 and 2.

Figure 4 is a bottom view, partly broken away, showing details of construction of a 25 louvre.

Figure 5 is an end view of a louvre.

Figure 6 is a bottom view of a bearing pin pad.

Figure 7 is an end view of same.

30 Figure 8 is a perspective top view of one end of a louvre.

Figure 9 shows a member for operating the louvres; and

Figure 10 shows the form of the spring 35 seen in Figure 1.

The same numerals refer to corresponding parts in the different figures of the drawing.

In Figures 1 and 2 the side rails 1 and 2 have straps 3 and 4 bending around the corners and riveted to end rail 5, as indicated. In Figure 3 is shown a section of end rail 5, with its U shaped lower member 6, in which the bearing holes 6' for the louvre pins are formed.

45 In Figure 4 is shown one louvre partly formed. At one end a small extension of the metal is pressed into cylindrical form to provide the bearing pin 7 and a knob-like member 8 which serves as a spacer to prevent the 50 leaf of the louvre from touching the end rail.

The pin 7 and spacer 8 are seen in end view in Figure 5. In Figures 6 and 7 is seen a small pad 9 of sheet metal with pin 10 and spacer 11 pressed in the same shape as 7 and 8, with holes 12 matching holes 13 in Figure 4 for riveting the pad on the louvre to provide pin and spacer for its other end. For at this end of the louvre an extension of the metal is formed into the half circle 14, which is bent up at right angles, as seen in Figure 8, and a further extension 15 is bent forward to form the arc shaped rim 15 seen in Figure 8.

In Figure 2 the pads 9 are seen riveted to the under side of the louvres, with pins 10 indicated in dotted lines extending through the U shaped bottom member 6 of end rail 5. By forming the member 6 in a round U shape, with only space enough inside the U for the bearing pins, the bearing holes must 70 pass through the metal wall of member 6 diagonally in the curve, so that the bearing surface of the hole is considerably increased for the pin to turn in, preventing rapid wear of bearing holes.

In Figure 1, it is the farther end rail that is indicated at 5, the nearer end rail being removed to show shifting bar 16 with two notches 17 and 18 and tooth 19 between the notches. Bar 16 has a pair of notches and a tooth for each louvre contained in the box. The tooth projects downward through hole 20 in rim 15. Figure 2 is a bottom view so that the point 21 of tooth 19 is seen in hole 20, where part of the U-member 6 of the end 85 rail is broken away.

A trip member 22, seen in Figure 9, is formed on strip 23, which is riveted to bar 16 so as to stand up above the face grill not shown, which covers a register box when in 90 service, so that the louvres may be opened or closed with the foot, or otherwise. It is easily understood from Figure 1 how the moving of bar 16 will rotate all the louvres on their pins. The particular value of this construction is its compactness and its ease and smoothness of operation, due to the three impulses given by the shifting bar to the louvres during the shift. For while tooth 19 gives the impulse in hole 20 during the mid 95 100

part of the shift, the sides 24 and 25 of the notches make contact with the ends of arc 15 and give the impulse during the remainder of the shift in either direction, having the effect of a rack and gear with several teeth. 5 Tooth 19 is of such shape, having sides at about 30 degrees angle to each other, or 15 degrees from the vertical, that it nearly fills hole 20 in all positions of arc 15, preventing lost motion.

10 Shifting bar 16 is held down by spring 26, seen in Figures 1 and 10, which is inserted between bar 16 and strip 23 and clamped between them in the position shown in Fig. 1 15 when they are riveted together. In Figure 1 are seen bars 27, 27, which span the register box from one end rail to the other to strengthen the top grill, not shown. Spring 26 presses up into notches in the under side 20 of bars 27 and down against bar 16 and strip 23, and so holds bar 16 snugly down with its notches astride the metal bordering hole 20 of the arcs, to prevent rattling during operation. The spring is provided with two humps, 25 as shown, which pass under bars 27 and serve to retain the moving parts in either open or closed position. This action of the spring is similar to that of the spring which holds the push button of an electric switch in its inner 30 or outer position.

The invention is not intended to be limited to the form or any of the details shown, but to embrace the scope of the following claims.

What is claimed is:

- 35 1. In a register, the combination of a plurality of sheet metal louvres; at one end of each louvre a small extension of its metal formed into a cylindrical bearing pin and spacer knob, said extension being integral 40 with the louvre along the entire width of the extension, the knob being formed by rolling up the sides of the extension next to the louvre into the form of a dome open at one side, and the pin being formed by rolling up the sides 45 of the remaining portion of the extension until the edges are opposite each other; at the other end of each louvre a small pad of metal formed with similar bearing pin and spacer knob and attached to the louvre; at 50 this latter end of each louvre an extension of its metal bent at right angles upward, then at right angles forward again and formed into an arc rim concentric with the bearing pin and pierced with a hole; a frame for the 55 louvres having bearing holes to receive said bearing pins; and a shifting bar crossing the louvres having two notches and a tooth at each arc rim, with the tooth through the hole in the arc rim and the two notches 60 astride the metal of the arc rim bordering the hole.
2. In a register, the combination of a plurality of sheet metal louvres; bearing pins at the ends of each louvre; an arc rim at one end of each louvre; a frame for the louvres

having bearing holes for said bearing pins; strengthening bars spanning the frame; a shifting bar under the strengthening bars crossing the louvres and having members cooperating with the arc rims 70 for rotating the louvres on their pins; a trip member attached to the shifting bar for shifting the latter; and a leaf spring held at its ends between the shifting bar and trip member, having sliding pressure against the 75 strengthening bars for preventing rattle of the parts and said springs having bowed portions for retaining the parts in whichever position they have been set.

3. In a register, a sheet metal louvre having an extension at one end, the extension being integral along its entire width with the louvre, and the sides of said extension at the inner or base end being rolled up towards each other to form a stop substantially in the 80 shape of a dome with one side open, and to form a cylindrical pin outward of said stop.

4. In a register, a sheet metal louvre, a sheet metal plate secured to one end of the louvre, said plate having an extension projecting beyond one end of the louvre, the extension being integral along its entire width with the plate, and the sides of said extension at the inner or base end being rolled up towards each other to form a stop substantially in the 85 shape of a dome with one side open, and to form a cylindrical pin outward of said stop.

5. In a register, a louvre having an extension at one end bent up at right angles to the 100 plane of the louvre, said extension having an arc-shaped flange bent outward at right angles thereto, and a hole through said flange substantially midway the ends of the arc.

6. In a register, a louvre having a substantially semi-circular extension at one end bent up at right angles to the plane of the louvre, said extension having an arc-shaped flange bent outward at right angles thereto from its edge near one end of the semi-circle, a hole 110 through said flange substantially midway the ends of the arc, and a shifting bar having two notches forming an intermediate tooth, the tooth projecting through the hole in the flange, and the outer walls of the notches engaging the edges of the flange at the ends of the arc.

7. In a register, the combination of a plurality of pivoted louvres, a frame for the louvres, strengthening bars spanning the frame, a shifting bar under the strengthening bars crossing the louvres and having members for rotating the louvres on their pivots, a strip attached to the shifting bar, and a leaf spring held at its ends between the shifting bar and strip, having sliding pressure against the strengthening bars for preventing rattle of the parts, and said spring having bowed portions for retaining the parts in whichever position they have been set.

8. In a register, the combination of a plurality of pivoted louvres, a frame for the louvres, strengthening bars spanning the frame, a shifting bar under the strengthening bars crossing the louvres and having members for rotating the louvres on their pivots, and a leaf spring secured at its ends to the shifting bar, said spring having sliding pressure against the strengthening bars for preventing rattle of the parts, and said spring having bowed portions for retaining the parts in whichever position they have been set.

In testimony whereof I affix my signature.
JOHN J. BURGESS.
